SWITCH

Ray W. Scott, Detroit, Mich., assignor to Bendix Home Appliances, Inc., Detroit, Mich., a corporation of Delaware

Application September 11, 1937, Serial No. 163,357

8 Claims. (Cl. 200—67)

This invention relates to switches, and is illustrated as embodied in a switch suitable for operation by the float of an automatic washing machine.

5 An object of the invention is to provide a snap-action switch which can be effectively and reliably operated by the relatively small power available from the movements of such a float, or the equivalent. Various features of novelty relate to the 10 construction and arrangement of the parts to give sufficient sensitivity of operation without interfering with the certainty and effectiveness of the snap action.

These and other objects and features of the 15 invention will be apparent from the following description of the illustrative embodiment shown in the accompanying drawing, in which:

Figure 1 is a side elevation of the switch, with the contacts in engagement, and with the casing 20 removed from its mounting in the washing machine;

Figure 2 is a similar view with the contacts separated;

Figure 3 is a bottom plan view;

Figure 4 is a transverse section on the line 25 4—4 of Figure 3; and

Figure 5 is an elevation of a modified form.

The particular switches shown are intended for operation by the float (not shown) of an automatic washing machine of the type described and claimed in application No. 129,429, filed 30 March 6, 1937, by Rex Earl Bassett, Jr., and John W. Chamberlin, and in application No. 129,412, filed March 6, 1937, by Adiel Y. Dodge.

35 The float is intended to be connected, by a connecting rod or link (not shown), with a lever 10 having one end formed into an eye 12 to constitute attaching means, and having its other end bent at right angles to form a pivot 14 mounted in lugs 16 forming part of a switch casing 18 or other support. The particular lever 10 illustrated is made from a piece of heavy wire.

40 The casing 18 may be molded or otherwise formed, and is preferably made of one of the phenolic condensation materials which forms a good insulator. The casing 18 cooperates with the part of the washing machine chassis to which it is secured (for example by screws threaded into sockets 22) to house the switch described 45 below.

A seat 24 is molded into one end of the casing, and on this are secured by means such as a screw 26 two spring metal contacts 28 and 30 separated by an insulator block 32. An insulator bushing 34 is sleeved on the screw 26. The contacts 28 and 30 have spaced ends 36 and 38 to which may be attached in any desired manner the wires leading to the circuit to be controlled by the float.

45 The contacts 28 and 30 are biased to spring 60 yielding apart, and normally separate to break

the circuit containing the switch. The ends of the contacts carry suitable contact parts 40 and 42 which can be brought into engagement to close the circuit.

5 The lower contact 30 also carries at its end a thrust button 44 or the like yieldingly held against a snap member such as a bowed leaf spring 46 confined at its ends, by a post 48 rigid with the casing 18, and by one wall of the casing. The post 48 and the casing wall are notched to receive 10 the ends of the bowed spring 46.

The ends of the contacts 28 and 30, and the center of the bowed spring 46 against which the contact 30 yieldingly holds its thrust part 44, are embraced between spaced parts such as jaws 50 15 and 52, shown formed as integral parts of a member 54 of insulating material. Member 54 passes through a slot 56 in the side wall of the casing 18, and is movable in a vertical plane at right angles to the contacts 28 and 30. It is mounted 20 on a pivot carried by the casing 18, the pivot shown being the transverse portion 14 of the lever 10, the lever 10 has another transverse portion 58 seated in a slot 60 formed in the edge of member 54, so that the lever oscillates member 25 54 in both directions.

Member 54 is preferably formed with lugs 62 and 64 engageable with the side wall of the casing 18 and serving as stops predetermined the open and closed positions of the movable switch 30 parts.

35 The distance between jaws 50 and 52 is slightly greater than the combined thickness of the parts 28—30—40—42—44 received between them, giving a clearance between contact parts 40 and 42 when the switch is open (Figure 2) and between jaw 52 and the bowed spring 46 when the switch is closed (Figure 1).

In operation, when the float (and therefore the lever 10) is down, with the machine empty 40 and while it is filling to a predetermined level, the switch is closed as shown in Figure 1. As the float rises, lever 10 is rocked upwardly, gradually tensioning the bowed spring 46 downwardly until, at some predetermined float level, the 45 spring 46 snaps past center to the position of Figure 2. This permits the contacts to separate and opens the switch.

The reverse happens as the float drops during the draining of the machine, the spring 46 50 being tensioned upwardly by jaw 52 until at a predetermined float level the bowed spring 46 snaps back to the position of Figure 1, closing the switch again.

Figure 5 shows a modified form of switch, parts 55 corresponding to parts in Figures 1-4 being designated by the same reference characters increased by 100. The principal difference is that the fixed ends of contacts 128 and 130 are not superposed as in the first modification, but are 60

secured to two seats 124 on opposite sides of the casing 118.

It will be noted that lever 10 has a very long lever arm, thereby giving very sensitive operation. Since contact 28 is held yieldingly against jaw 50 at all times, and contact 30 is yieldingly held at all times in a position determined by bowed spring 46, and since the bowed spring 46 yieldingly holds the contacts together when they are closed, all of the moving parts are at all times spring-loaded in positions determined by the stops 62 and 64.

While two illustrative embodiments have been described in detail, it is not my intention to limit the scope of the invention to those particular embodiments, or otherwise than by the terms of the appended claims.

I claim:

1. A switch comprising a casing, a member pivoted on the casing and having two stops engageable with the casing to determine two extreme positions and which is provided inside the casing with spaced jaws, spring contacts inside the casing one of which is biased toward and yieldingly held against one of said jaws and the other of which is biased to spring yieldingly away from said one contact and said one jaw thereby tending to separate said contacts, and a bowed resilient member confined at its ends and arranged at its center between the other jaw and said other contact and which is operated by movement of the jaws to snap suddenly past its center position in opposite directions to close and separate said contacts.

2. A switch comprising a casing, a member movably mounted on the casing and which is provided inside the casing with spaced jaws, spring contacts inside the casing one of which is biased toward and yieldingly held against one of said jaws and the other of which is biased to spring yieldingly away from said one contact and said one jaw thereby tending to separate said contacts, and a bowed resilient member confined at its ends and arranged at its center between the other jaw and said other contact and which is operated by movements of the jaws to snap suddenly past its center position in opposite directions to close and separate said contacts.

3. A switch comprising a pair of spring contacts engageable with each other and biased to spring yieldingly apart, a bowed leaf spring confined at its ends and with its center engaging the end of one of said contacts and with said one contact yieldingly held against said center, said bowed leaf spring in one position permitting the contacts to separate and when snapped past center to its other position holding said contacts in engagement, and operating means including connected spaced parts between which the ends of the contacts and the center of the bowed spring are arranged and which parts are movable to cause the bowed spring to snap back and forth past center.

4. A switch comprising a pair of spring contacts engageable with each other and biased to spring yieldingly apart, a bowed resilient member confined so that it passes with a snap action between two positions and with its center engaging the end of one of said contacts and with said one contact yieldingly held against said center, said bowed member in one position permitting the contacts to separate and when snapped past cen-

ter to its other position holding said contacts in engagement, and operating means including connected spaced parts between which the ends of the contacts and the center of the bowed member are arranged and which parts are movable to cause the bowed member to snap back and forth past center.

5. A switch comprising a casing, a member pivoted on the casing and having two stops engageable with the casing to determine two extreme positions and which is provided inside the casing with spaced jaws, spring contacts inside the casing one of which is biased toward and yieldingly held against one of said jaws and the other of which is biased to spring yieldingly away from said one contact and said one jaw thereby tending to separate said contacts, and a bowed resilient member confined at its ends and arranged at its center between the other jaw and said other contact and which is operated by movements of the jaws to snap suddenly past its center position in opposite directions to close and separate said contacts, said member with the jaws being of insulating material and having associated therewith a lever pivoted on the casing and having a portion operatively engaging a recess in the member.

6. A switch comprising a casing, a member movably mounted on the casing and which is provided inside the casing with spaced jaws, spring contacts inside the casing one of which is biased toward and yieldingly held against one of said jaws and the other of which is biased to spring yieldingly away from said one contact and said one jaw thereby tending to separate said contacts, and a bowed resilient member confined at its ends and arranged at its center between the other jaw and said other contact and which is operated by movement of the jaws to snap suddenly past its center position in opposite directions to close and separate said contacts, said member with the jaws being of insulating material and having associated therewith a lever pivoted on the casing and having a portion operatively engaging a recess in the member.

7. A switch comprising a support having mounted thereon two spring contacts biased to spring apart at their ends and having portions adjacent their other ends separated by an insulator and secured to the support, a bowed leaf spring having its ends so confined that it snaps back and forth between two positions on opposite sides of center and having its center operatively engaging the first end of one of said contacts, and actuating means including connected spaced parts embracing between them the first ends of the contacts and the center of the bowed spring.

8. A switch comprising a support having mounted thereon two spring contacts having their ends secured to opposite sides of the support and having contact portions at the center of the support engageable with each other and biased to spring apart, a bowed leaf spring having its ends so confined that it snaps back and forth between two positions on opposite sides of center and having its center operatively engaging the contact portion of one of said contacts, and actuating means including connected spaced parts embracing between them the first ends of the contacts and the center of the bowed spring.
